UNITED STATES PATENT OFFICE.

GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

ROCK-DRILL.

1,164,496.

Specification of Letters Patent. Patented Dec. 14, 1915.

Application filed March 20, 1912, Serial No. 684,967. Renewed April 29, 1915. Serial No. 24,803.

To all whom it may concern:

Be it known that I, GEORGE H. GILMAN, a citizen of the United States, and a resident of Claremont, county of Sullivan, State of New Hampshire, (whose post-office address is Claremont, New Hampshire,) have invented an Improvement in Rock-Drills, of which the following description, in connection with the accompanying drawings, is a specification, like characters on the drawings representing like parts.

This invention relates to stone working machines and more particularly, though not exclusively, to rock drills of the reciprocating type provided with means for supplying water together with compressed air or other gaseous fluid to the drilled hole for the purpose of washing out therefrom the pulverized stone and cuttings which have been displaced by the tool.

The invention will be best understood by reference to the following description when taken in connection with the accompanying illustration of one specific embodiment thereof, while its scope will be more particularly pointed out in the appended claims.

In the drawings: Figure 1 is a longitudinal section of a common type of rock drilling machine to which is applied one form of my invention. Fig. 2 is a detail longitudinal section of a portion of the piston and water tube showing the latter withdrawn from the passage in the piston rod. Fig. 3 is a cross-sectional view on a much enlarged scale of the rifle-bar and the bushing in which it reciprocates.

Referring to the drawings, I have there shown for the purpose of illustrating the principal features of the invention, a rock drill having the piston 1 and the cylinder 2, the cylinder being mounted upon a usual shell 3 on which it is adapted to be fed toward the work by the feed screw 4 and handle 5 through the usual connections. The piston rod 6 which projects through the forward cylinder head 7 terminates in the tool holding chuck 8 in which any suitable form of bit 9 is held fixed against rotation by a common type of clamp 8^x.

The bit is herein shown as consisting of a section or length of straight hollow drill steel having a hexagonal cross section. It

terminates in the cutting edge 10 and has an axial passage 11 from end to end. Any usual or suitable form of controlling valve 55 may be employed for admitting pressure fluid (which is preferably compressed air but may be steam or other elastic gaseous fluid) to the opposite ends of the cylinder through the ports 12 and 12^x, but herein a valve 13 of the pressure-actuated piston type is shown which is reversed by means of the reverse ports 14 and 15, the latter shown in dotted lines as leading from opposite ends of the valve chamber to the circumferential grooves 16 and 17, respectively, of the cylinder.

The movement of the piston in either direction uncovers one of the cylinder grooves 16 or 17 and admits pressure fluid from behind the piston to one end of the valve to throw the same in the opposite direction, the opposite end of the valve chamber being simultaneously opened to the exhaust by the uncovering of the remaining cylinder groove 75 to a longitudinal groove 18 formed in the piston and communicating with a central piston groove 19, the latter being open to a cylinder groove 20 which communicates with the exhaust port. This form of pressure-actuated piston controlled valve is well known and is shown merely as illustrative of any suitable type of controlling valve, the invention not being limited to this or any other valve construction.

At each stroke of the piston the latter, together with its attached tool is given a slight rotative movement, as is usual in this class of devices, preferably by suitable automatic rotating mechanism. Herein such rotating mechanism comprises the spirally grooved rifle bar 21 engaging the spirally toothed nut 22 secured in the rear head of the piston. The rifle bar 21, as is customary, is permitted a rotative movement in one direction as the piston moves forwardly, but is locked against rotative movement on the reverse stroke of the piston so as to compel the step-by-step rotative movement of the latter. The means for holding the rifle bar 90 rotatively fixed in one direction only herein comprises the usual ratchet 23 secured to the rifle bar and combined with roller clutch pins 24 of a common type such as is shown

in prior patent to Officer No. 580,461, this, however, being merely disclosed as illustrative of any suitable rotating mechanism.

To direct a supply of water to the drilled hole the piston rod and piston are suitably formed to receive the water tube or pipe 25 adapted to introduce water under pressure into the passage 26 in the piston rod whence it flows to the passage 11 through the drill 5 steel to the cutting edge 10 thereof. The water tube 25 may be held in any suitable manner so as to be adjustable longitudinally, but herein its rear end is gripped by the yieldable washer 27, preferably of rubber or other similar material, such washer being seated in an axial cavity formed in the cylinder headblock 28. The rubber washer 27 is backed by a disk 29 preferably of steel or other suitable metal, which is forced 10 down upon the rubber washer by means of the threaded gland 30 to compel the washer to adjustably grip the tube. The water pipe which is thus adjustably gripped by the rubber washer 27, projects with a sliding fit 15 through an axial opening in the rifle bar 21 and into the hollow passage 26 of the piston rod with which it also has a sliding fit. The rear end of the tube projects through the washer 27 and the steel disk 29 20 into the central passage of the gland 30, which latter is provided with the connection 31 through which water under pressure may be supplied by a flexible or other pipe 25 connection from an elevated reservoir, force pump, or other suitable source, not shown.

In order to unite the water in the form of spray, a portion of the exhaust pressure fluid or a portion of the live pressure fluid behind the piston is caused to escape into 30 the interior of the piston and, when the latter has reached a certain part of the stroke, which may be determined by the adjustment of the water tube is caused to enter the axial passage 26 to meet the water discharged through the tube 25, the water and pressure fluid passing forward through the drill bit and being discharged at the cutting edge thereof, acting to keep the bottom of the hole clean.

To cause the introduction of the pressure fluid into the piston passage 26 the rifle bar chamber 32 is prolonged or counterbored at 40 33, the prolonged portion extending far enough so that when a certain predetermined position is reached by the piston on its forward stroke the forward end of the water tube 25 may be uncovered or opened to the counterbored portion 33 of the rifle bar chamber and either live or exhaust 45 fluid pressure accumulated therein is allowed to escape into the passage 26 in front of the tube and unite with the stream of water therein. Thus the portion of the piston rod which cooperates with the forward 50 end of the water tube constitutes a means

for intermittently opening the water feed tube to the pressure fluid in the cylinder. The forward end of the water tube constitutes a valve for intermittently opening the fluid supply passage of the piston to a 55 source of pressure fluid, herein the rifle bar chamber. By this means a very economical operation of the tool is secured, owing to the fact that the release of the pressure fluid to the drill bit is intermittent, and further owing to the fact that exhaust pressure fluid may be utilized. The exhaust position of the piston on its forward stroke is reached when it uncovers the valve reverse groove 60 16. The pressure fluid within the rear end of the cylinder is then exhaust pressure fluid, since the valve is reversed and live pressure fluid is no longer supplied to the rear end of the cylinder. The clearance between the grooves of the rifle bar 21 and the teeth of the nut 22 permits a reasonably free passage or interchange of the actuating fluid between the rifle bar chamber 32 and the cylinder chamber behind the piston, the result being that at each forward stroke 65 of the piston a portion of either live or exhaust fluid from behind the piston as the conditions of the work may require, may be released through the rifle bar chamber 32, the counterbored portion 33 and piston rod passage 26 and may act to drive the water through the drill bit passage and into the bottom of the hole in the form of spray, serving to expel the cuttings at each stroke 70 of the tool. Thus at each stroke of the piston there is added to the steady stream of water flowing through the tube a puff or injection of air of just the required force according to the conditions of the work, this taking place during and preferably at or 75 near the end of the downward or working stroke so that it is effective in acting on the cuttings loosened by the stroke. When the water tube is placed in the position shown in the drawing, the forward end of the tube is 80 uncovered or opened to the counterbored portion 33 of the rifle bar chamber at the proper time in the stroke of the piston to release exhaust pressure fluid into the passage 26. The amount of the pressure fluid 85 thus released may be varied by varying the position of the tube longitudinally within certain limits. By adjusting the tube rearwardly beyond these limits, the end of the tube will be uncovered so early in the stroke 90 as to release live pressure fluid into the passage 26. By adjusting the tube forwardly to a sufficient extent, the end of the tube will not be uncovered during any part of the stroke, and consequently the supply of pressure fluid through the drill bit will be entirely cut off. Thus it will be seen that by proper adjustment of the water tube, the pressure fluid supply through the drill bit 95 may be regulated to suit the conditions of 100

the work on which the tool is operated, it being possible to secure the delivery from the drill bit of water alone, water and exhaust pressure fluid, or water and live pressure fluid. The water may be controlled or regulated by any suitable means such as the hose line valve 35.

5 If desired the supply of water might be wholly cut off and the tool used with pressure fluid alone; the water being introduced independently into the hole, or, by omitting the counterbore 33, the drilling may be performed under the cleansing action of water alone.

10 15 If desired a perforated packing washer 34 may be employed between the shank of the cutter bit 9 and the seat in the chuck 8 so as to prevent leakage of water through the chuck.

20 25 While I have herein shown and described for the purpose of illustration one specific form of the invention, it is to be understood that the same is submitted for illustrative purposes only and that extensive deviations may be made from the disclosed form thereof without departing from the spirit of the invention.

Claims:

1. In a rock drill, the combination with a cylinder, a piston having a chamber and a piston rod having an axial passage terminating in said chamber, a rifle-bar extending into said chamber, a fluid supply tube secured to said cylinder and projecting axially 30 through said rifle-bar, said chamber and into said axial piston passage, said tube being of such length as to alternately enter and withdraw from said passage to alternately open and close the latter to said chamber during the reciprocation of said piston.

2. In a rock drill, the combination with a cylinder, piston, rifle bar, said piston being provided with a rifle bar chamber and an axial passage, a fluid supply tube projecting through the rifle bar and its chamber into said passage and means coöperating with the forward end of said tube constituting a valve for intermittently admitting to said passage at each piston stroke a quantity of pressure fluid from the rifle bar chamber to the said piston passage.

3. In a rock drill the combination with a cylinder, of a piston, a rifle bar, said piston being provided with a rifle bar chamber 55 and an axial passage, and said chamber having free communication at all times past the rifle bar with the cylinder chamber, means for feeding water through the rifle bar into the piston passage, and means for also intermittently introducing into said piston passage pressure fluid from the rifle bar chamber.

4. In a rock drill the combination with a cylinder, a piston provided with a rifle-bar chamber, a rifle bar, said piston and rifle

bar being provided each with an axial passage, means for introducing water through the rifle bar into the piston passage and means for admitting pressure fluid from the cylinder also into said piston passage only 70 when the exhaust position of the piston is reached.

5. In a rock drill the combination with a cylinder, a piston provided with a rifle-bar chamber, a rifle bar, said piston and rifle 75 bar being provided each with an axial passage, means for introducing water through the rifle bar into the piston passage and means for admitting only exhaust pressure fluid into said piston passage to intermingle 80 with said water.

6. In a rock drill the combination with a cylinder, a piston and rifle bar, said piston and rifle bar each being provided with a fluid supply passage, means for introducing 85 water through the rifle bar into the said piston passage, and means also for introducing the exhaust pressure fluid into said piston passage from the rear of the cylinder after the supply of live pressure fluid to the 90 rear end of the cylinder has been cut off.

7. In a rock drill the combination with a cylinder, of a piston, a rifle bar, said piston being provided with an axial passage, a fluid supply tube for introducing water 95 through said rifle bar into said passage, and means for utilizing relative motion of said piston and tube for intermittently introducing into said passage exhaust pressure fluid from the rear of the cylinder.

8. In a rock drill the combination with a cylinder, a piston and a rifle bar, said piston being provided with an axial passage and a rifle bar chamber, a fluid supply tube projecting through the rifle bar and its 105 chamber and being of such length as to be intermittently opened to the pressure fluid in said rifle bar chamber.

9. In a rock drill the combination with a cylinder, piston and rifle bar, said piston 110 being provided with a fluid supply passage and a rifle bar chamber, said chamber communicating at all times with the pressure fluid at the rear of the piston for the passage of said fluid past the rifle bar, and means for intermittently opening the fluid supply passage of said piston to the rifle bar chamber.

10. In a reciprocatory rock drill the combination with a cylinder of a piston and a rifle bar, a fluid supply passage in said piston, a water feed tube entering the rifle bar for delivering water to said passage, and means for intermittently placing the forward end of said feed tube in communication 120 with the exhaust pressure fluid in the cylinder.

11. In a reciprocatory rock drill the combination with a cylinder, a piston, a fluid supply passage in the piston, a fixed water 130

feed tube for delivering water to said piston passage, and means for intermittently placing the forward end of said feed tube in communication with the exhaust fluid pressure in the cylinder.

12. In a reciprocating rock drill the combination with a piston, a cylinder, a rifle bar, said piston having a rifle bar chamber communicating with said cylinder and a fluid supply passage communicating with said chamber, a feed tube passing through the rifle bar for introducing water into said piston passage, and means for intermittently opening the said piston passage to the pressure fluid in said rifle bar chamber.

13. In a reciprocating rock drill the combination with a piston, a cylinder, a rifle bar, said piston having a rifle bar chamber communicating with said cylinder and a fluid supply passage communicating with said chamber, a feed tube passing through the rifle bar for introducing water into said piston passage, and means for intermittently opening the said piston passage to the exhaust pressure fluid in said rifle bar chamber after the supply of pressure fluid to said cylinder has been cut off.

14. In a rock drill, the combination with a cylinder, of a drill bit provided with a fluid supply passage arranged to communicate with said cylinder, a water feed tube communicating with said passage, and a piston having means cooperating with said tube to alternately open and close communication between said passage and said cylinder.

15. In a rock drill, the combination with a cylinder member and a piston member, of a drill bit provided with a fluid supply passage arranged to communicate with said cylinder, and a water feed tube communicating with said passage and secured to one of said members, said tube being of such length and so positioned as to utilize the reciprocatory movement of said piston to alternately open and close communication between said passage and said cylinder.

16. In a rock drill, the combination with a cylinder, of a piston provided with a fluid supply passage arranged to communicate with said cylinder, a water-feed tube communicating with said fluid supply passage and means cooperating with said feed tube for utilizing the reciprocatory movements of said piston to open and close communication between said cylinder and said passage.

17. In a rock drill, the combination with a cylinder, of a drill bit provided with a fluid supply passage arranged to communicate with said cylinder, a piston provided with a fluid supply passage communicating with the drill bit passage, a water-feed tube communicating with said fluid supply passage and means cooperating with said feed tube for utilizing the reciprocatory movement of

said piston to open and close communication between said piston passage and said cylinder.

18. In a rock drill, the combination with a cylinder, of a piston provided with a fluid supply passage arranged to communicate with said cylinder, means for utilizing the reciprocatory movements of said piston to open and close communication between said passage and said cylinder, and means for enabling the point of the piston stroke at which said passage is opened to be varied.

19. In a rock drill, the combination with a cylinder, of a piston provided with a fluid supply passage, and means for utilizing the reciprocatory movement of said piston to alternately open and close said passage to the live pressure fluid or the exhaust fluid after the supply of pressure fluid to the cylinder has been cut off.

20. In a rock drill, the combination with a cylinder, of a tool-actuating piston provided with a fluid supply passage leading directly to and communicating at all times with the drill-tool, a valve acting to utilize the reciprocatory movement of said piston to alternately open and close said passage, and means permitting longitudinal adjustment of said valve.

21. In a rock drill, the combination with a cylinder, of a piston provided with a fluid supply passage, and a valve acting to utilize the reciprocatory movement of said piston to alternately enter and withdraw from said passage.

22. In a rock drill, the combination with a cylinder, of a piston provided with a fluid supply passage, and a water feed tube utilizing the reciprocatory movement of said piston to alternately open and close said passage.

23. In a rock drill, the combination with a cylinder, of a piston provided with a fluid supply passage, a water feed tube utilizing the reciprocatory movement of said piston to alternately open and close said passage, and means for adjustably securing said tube while permitting longitudinal adjustment of the same.

24. In a rock-drill, the combination of a cylinder, a piston provided with a fluid supply passage, and a valve acting to utilize the reciprocatory movement of said piston to alternately open and close said passage.

25. In a rock drill, the combination of a drill-bit, a reciprocating drill-bit actuating member provided with a fluid supply passage leading toward the cutting end of said drill-bit, and means acting to utilize the reciprocatory movement of said member to alternately open and close said passage.

26. In a rock drill, the combination of a hollow drill-bit, a reciprocating drill-bit actuating member provided with a fluid supply passage communicating with the inte-

rior of said drill-bit, and means acting to utilize the reciprocatory movement of said member to alternately open and close said passage.

5 27. In a rock-drill, the combination of a drill-bit, separate conduits for conducting supplies of gaseous fluid and liquid toward the cutting end of said drill-bit, and means for causing relative reciprocatory movement of said conduits to interrupt and re-establish the flow of said gaseous fluid.

10 28. In a rock-drill, the combination of a drill-bit, separate conduits for conducting supplies of gaseous and liquid fluid toward the cutting end of said drill-bit and commingling said fluids, and means for causing relative reciprocatory movement of said conduits to interrupt and re-establish the flow of one of said fluids.

15 29. In a rock drill, the combination of a drill-bit, coaxially arranged conduits for conducting supplies of gaseous and liquid

fluid toward the cutting end of said drill-bit and commingling said fluids, and means for causing relative reciprocating movement 25 of said conduits to produce a pulsatory character of the stream of fluid.

30 30. In a rock drill, the combination of a drill-bit, coaxially arranged conduits for conducting supplies of gaseous and liquid 30 fluid toward the cutting end of said drill-bit and commingling said fluids, one of said conduits discharging into the other, and means for causing relative reciprocatory movement of said conduits to establish and 35 interrupt communication between said conduits.

In testimony whereof, I have signed my name to this specification, in the presence of two subscribing witnesses.

GEORGE H. GILMAN.
